UNITED STATES PATENT OFFICE

105,277

DESIGN FOR A CHAIR

Edwin R. Hewitt, Grand Rapids, Mich.

Application April 8, 1937, Serial No. 68,612

Term of patent 3½ years

To all whom it may concern:

Be it known that I, Edwin R. Hewitt, a citizen of the United States, residing at Grand Rapids, in the county of Kent and State of Michigan, have invented a new, original, and ornamental Design for a Chair, of which the following is a specification, reference being had to the accompanying drawing, forming a part thereof, in which:—

The distinguishing or characteristic features of the design of the chair reside in the sides thereof forming the chair arms, which sides encircle the chair back rearwardly thereof, as shown.

I claim:

The ornamental design for a chair as shown and described.

EDWIN R. HEWITT.
